(57) CLAIM

The ornamental design for an flower box, as shown and described.

DESCRIPTION

FIG. 1 is a perspective view of a flower box, showing my new design;

FIG. 2 is another perspective view thereof;

FIG. 3 is a side view thereof, the opposite side being a mirror image;

FIG. 4 is a front view thereof;

FIG. 5 is a back view thereof;

FIG. 6 is a top view thereof; and,

FIG. 7 is a bottom view thereof.

The parts colored in white and delineated with broken lines illustrate portions which are not part of the claimed design.

1 Claim, 7 Drawing Sheets
